UNITED STATES PATENT OFFICE.

THOMAS H. WRIGHT, OF LOS ANGELES, CALIFORNIA.

MONORAIL STRUCTURE.

Application filed September 15, 1922. Serial No. 588,430.

To all whom it may concern:

Be it known that I, THOMAS H. WRIGHT, a citizen of the United States, residing at Los Angeles in the county of Los Angeles 5 and State of California, have invented new and useful Improvements in Monorail Structures, of which the following is a specification.

My invention relates to monorail structures, and a purpose of my invention is the provision of a monorail structure of extremely simple, durable and efficient construction, and which includes means for effectively bracing a car against lateral 10 movement when traversing the monorail so that the car is at all times perfectly balanced to eliminate friction and insure of the easy 15 propulsion of the car with a minimum amount of power.

Although I have herein shown and described only one form of monorail structure embodying my invention, it is to be understood that various changes and modifications 20 may be made herein without departing 25 from the spirit of the invention and the spirit and scope of the appended claims.

In the accompanying drawings,

Figure 1 is a view showing in end elevation one form of monorail structure embodying my invention and having applied thereto one form of car.

Fig. 2 is a side elevation of the car and monorail structure shown in Fig. 1.

Referring specifically to the drawings in which similar reference characters refer to similar parts, my invention in its present embodiment comprises main supporting beams 15 arranged at regular intervals and sustained in vertical position by means of 30 brace bars 16 connected at their upper ends to the upper ends of the beams 15 and diverging to spaced points where they are connected at their lower ends to ties 17. Sustained upon the beams 15 are longitudinally 35 extending beams or ties 18, and secured upon the beams 18 is a monorail 19. A rack 20 is also secured to the beams 18 and is disposed in spaced parallel relation to the rail 19 for a purpose which will be 40 hereinafter described.

The brace bars 16 support ties or beams 21 which are of substantially triangular shape in cross section, and secured to these beams and bars are rails 22 having vertically disposed surfaces against which guide 45 rollers 23 are adapted to bear. These rollers

23 are carried by vertically disposed shafts 24 movably sustained on a car adapted for movement over the monorail. The shafts in turn are journaled in substantially H-shaped 60 yoke carriages 24^a, the parallel portions of which are slidably mounted in yokes 24^b sustained at the under side of the vehicle body. Coiled expansible springs 24^c are mounted upon the parallel portions of the carriages 65 24^a and are interposed between one portion of the yoke and washers 24^d so that the springs normally urge the carriages in the direction of the rails 22 to cause the rollers 23 to have a yielding contact with the rails. 70

The car, in the present instance, comprises a body 25 which is relatively wide, and which as shown in Fig. 1, is provided centrally thereof with a longitudinally extending opening 26 to allow for the accommodation 75 of the upper part of the monorail structure. This opening 26 communicates at its lower end with an inverted V-shaped opening 27 designed to accommodate the diverging brace bars 16, as will be understood. The 80 shafts 24 of the rollers 23 depend from the lower side of the car body 25, and as shown, the rollers are disposed to contact with the outer sides of the rails 22.

The car is supported for movement on the monorail 19 by means of grooved wheels 28 fixed to shafts or axles 29, the latter being arranged adjacent the opposite ends of the car body 25, as indicated in dotted lines in Fig. 2. Each shaft 29 is provided with a 90 worm gear 30 which constantly meshes with a worm 31, and the two worms 31 are adapted to be driven simultaneously through the medium of a motor designated generally at 32. Each shaft 29 also carries a spur gear 95 33 which constantly meshes with the rack bar or rail 20 so as to provide a positive driving connection in effecting a propulsion of the car.

In operation, the entire weight of the car 100 is actually supported by the monorail 19, and properly distributed by the arrangement of the grooved wheels 28. The guide rollers 23 engage with the rollers 22 to prevent any lateral swaying of the car body 105 during movement of the car over the monorail, and because the rollers have rolling contact with the rails, it will be clear that any lateral movement of the car is prevented without undue friction. The rack rail 20 being 110 engaged by the spur gears 33 naturally provides a positive driving means for the car

thus eliminating the necessity of depending upon traction between the monorail and the wheels 28. This naturally permits of the provision of a relatively small monorail, and 5 wheels 28 having relatively narrow peripheries.

The arrangement of the beams and bars is such as to provide an extremely strong and durable supporting structure for the 10 monorail 19 so that the latter is capable of accommodating the cars of relatively great weight, or cars carrying relatively heavy loads.

What I claim is:

- 15 1. A monorail structure comprising spaced ties, vertically disposed beams supported on the ties, horizontally disposed beams connecting the vertical beams and adapted to support a monorail thereon, divergent brace 20 bars connecting the vertical beams and said ties, horizontally disposed beams connecting the brace bars of one vertical beam with an adjacent beam, and rails secured to the second horizontal beams.
- 25 2. In combination, a monorail structure comprising a monorail sustained in one plane, guide rails sustained in a plane below the monorail and at opposite sides of the latter, and a car including a body con-

structed to accommodate the monorail at a 30 point within the body, and wheels bodily movable by the car body and engaging said guide rails and means for constantly and yieldably urging the wheels into engagement with the guide rails.

3. A monorail car comprising a body, yokes secured to the body, H-shaped carriages slidably mounted in the yokes, rollers journaled at the yokes at the confronting ends thereof, and yieldable means for urging the yokes toward each other.

4. In combination, a monorail structure including a monorail and guide rails at opposite sides of the monorail, a car including a body, wheels bodily movable by the 45 car body, and means for constantly and yieldably urging the wheels into engagement with the guide rails.

5. A monorail car comprising a body, yokes secured to the body, H-shaped carriages slidably mounted in the yokes, rollers journaled in the yokes at the confronting ends thereof, and springs for urging the yokes toward each other for the purpose described.

In testimony whereof I have signed my name to this specification.

THOMAS H. WRIGHT.
